UNITED STATES PATENT OFFICE

2,130,158

SOUND RECORDING AND REPRODUCING DEVICE

Arno Rysick, Dresden, Germany

Application December 21, 1932, Serial No. 648,245
In Germany June 17, 1929

4 Claims. (Cl. 274—30)

The invention relates generally to sound recording and reproducing devices, and more particularly, to dictating machines adapted for the recording and subsequent reproducing of sound by the use of a single machine.

It is accordingly an object of the present invention to produce a unitary device operable to both record and reproduce sound impulses.

A further object of the invention resides in the provision of a machine of the class described, embodying separate recording and reproducing heads, adapted to be selectively moved into engagement with a recording disc by a single manipulative means.

Yet a further object of the invention resides in the provision of a recording and reproducing machine embodying a turntable adapted to support a disc of recording material, a carriage movable in a plane parallel to and spaced above the plane of said turntable, and separate recording and reproducing heads operatively supported on said carriage and adapted to be selectively moved into or out of engagement with a disc on said turntable by means of a single manipulative device.

Other objects and advantages will be in part obvious and in part pointed out hereinafter.

The invention accordingly consists in the features of construction, combinations of elements, and arrangements of parts as will be exemplified in the structure to be hereinafter described, and the scope of which will be indicated in the following claims.

In the accompanying drawing, in which is shown one of the various possible embodiments illustrative of this invention.

Fig. 1 is a fragmentary top plan view of a recording and reproducing device embodying a preferred form of the invention.

Fig. 2 is a fragmentary elevational view of the machine shown in Fig. 1.

Fig. 3 is an illustrative form of circuit arrangement which may be utilized in conjunction with electrical recording and reproducing in a machine of the type described.

Fig. 4 is an enlarged detail view of a part of the structure shown in Figs. 1 and 2.

Corresponding reference characters refer to corresponding parts throughout the several views of the drawing.

As conducive to a clear understanding of the invention, it is pointed out that in combined recording and reproducing machines it is highly desirable to be able to readily condition the machine for either a recording or reproducing operation. In the present instance, such purpose

is accomplished by providing a manipulative means common to both the recording and reproducing heads, and effective to selectively engage one or the other with a disc upon the machine, or in the alternative, to maintain both the recording and reproducing heads in their elevated or ineffective positions out of engagement with the material of the disc.

Referring now to Figs. 1 and 2, a rotatable turntable is indicated at 10, a vertically disposed shaft 11, journaled in any desirable manner in the housing of the machine being adapted to support the turntable for rotary movement in a fixed horizontal plane.

A carriage 12, is slidably supported for advancing and return excursions of movement in a horizontal plane, on spaced guide rods 13 and 14 rigidly supported at their respective ends in the frame of the machine. In the present instance, the rod 13 lies substantially in the plane of the turntable 10 and may be carried in upward extensions of the side frames (not shown). A suitable bore, provided in the carriage, is adapted to slidably receive the rod 13 and the lower portion of the carriage as shown particularly in Fig. 2, is bifurcated to form spaced parallel legs 15 and 16 which embrace the rod 14.

Means is provided to move the carriage, and in the present instance will be seen to comprise a feed screw 17 suitably journaled in the side frames of the machine and arranged to be drivably engaged with the carriage through the medium of a spring actuated segment 18 pivotally supported upon a short shaft 19, the ends of which are carried in the legs 15 and 16. In this connection it will suffice to point out that suitable provision is made for engaging and disengaging the segment 18 with the feed screw 17.

The carriage 12 includes a horizontally extending portion 20, which overlies the surface of the turntable 10 and operatively supports recording and reproducing heads 21 and 22 respectively. The heads 21 and 22 are independently and jointly movable in vertical planes and jointly movable in horizontal planes to selectively control engagement of one or the other with a recording disc 23, adapted to be carried on the upper surface of the turntable 10. To this latter end, the recording and reproducing heads are provided with rigidly formed and leftwardly extending tubular portions 24 and 25 which are journaled in pairs of similar, spaced parallel ears 26 and 27.

The ears 26 and 27 are formed integrally with a sub-carriage 28 movably supported at the right-hand end of the part 20, of carriage 12. A right-

wardly extending plate 28, fixed to the under surface of the carriage is turned upwardly at 30 to define a shoulder 31 which underlies the tubular portions 24 and 25 of the recording and reproducing heads and is thus adapted to support the latter. As shown in Fig. 4 the shoulder 31 of the part 30 is formed with a notch 32 intermediate its ends, the notch being of such depth as to permit a needle in either the recording or reproducing heads to engage a record on the turntable when its tubular part drops thereinto.

It will now be apparent that movement of the sub-carriage will function to selectively permit either the recording or reproducing heads to engage a disc upon the turntable or to cause both heads to be held out of engagement therewith. Means are provided to move the sub-carriage with respect to the carriage proper and thus predetermine the particular one of the heads which is to operatively engage the surface, or, in the alternative, to maintain both heads in ineffective position.

In the present instance the sub-carriage is actuated by means of a lever arm 33 pivotally supported intermediate its end in the part 20 of the carriage 12 by means of a vertically disposed pivot pin 34. The forward end of lever 33 is suitably articulated to the sub-carriage 28, its rear end being provided with a pin 35 which rides in the cam slot 36 of a cylindrically shaped cam 37 journaled within the upper end of the carriage 12 on an axis substantially parallel to those of the guide rods 13 and 14. In the present embodiment of the invention, cam 37 is fixed to a shaft 38 one end of which as shown in Fig. 1, is provided with an operating lever 39. It will be apparent that rotation of shaft 38 through the medium of lever 39 from the position shown in Fig. 1, will function to rotate the cam 37 thus imparting movement to the pin 35 of lever 33 so as to move the sub-carriage and its articulated recording and reproducing heads downwardly as viewed in Fig. 1. The extent of this movement of the operating lever 39 will determine whether the recording head will subsequently be permitted to drop into the notch 32 or whether both heads will be supported by the shoulder 31 of the part 30 of plate 28 so as to maintain both in ineffective position.

As shown in Fig. 3, the recording and reproducing heads may be electrically connected to a suitable amplifying means indicated generally at 40. A conductor 41 for example, is utilized to provide an electrical connection from the recording head 21 to the amplifier, and a conductor 42 similarly connects the reproducer 22 and the amplifying unit. A microphone 43 and loud speaker 44 are electrically connected with the amplifying unit through the medium of the conductors 45 and 46 and a conductor 47 may be connected to a suitable source of electrical energy. A conductor 48 may conveniently be employed to provide an electrical connection from a source of energy to a turntable driving motor (not shown), and a switch 49 mounted on the amplifying unit panel is interposed in the power line to the driving motor. A second switch 50 may be arranged to control the electrical circuit to the recording and reproducing heads.

It will be seen that I have provided a simple and economically manufactured means for selectively controlling recording and reproducing heads to cause one or the other to operatively engage a disc upon the turntable 10, or, in the alternative, to effectively maintain both heads in inoperative position.

I claim as my invention:

1. In a recording and reproducing device, the combination of a rotatable record carrier, a carriage supported for movement in a plane parallel with and overlying the record carrier, recording and reproducing devices operatively mounted on said carriage, a lever arm pivoted on said carriage and arranged to jointly move said recorder and reproducer relative to said carriage in a plane spaced above the plane of the record carrier, means on said carriage to support the recorder and reproducer above and out of engagement with a record on said record carrier, and to permit downward movement of either the recorder or reproducer into engagement with a record on said carrier in a single predetermined position, and manual means to actuate said lever.

2. In a recording and reproducing device, the combination of a rotatable record carrier, a carriage supported for movement in a plane parallel with and overlying the record carrier, recording and reproducing devices operatively mounted on said carriage for movement relative thereto, a lever arm pivoted on said carriage and arranged to jointly move said recorder and reproducer, a guiding ledge fixed to said carriage and underlying said recorder and reproducer, said guiding ledge serving to support the recorder and reproducer above and out of engagement with a record on said record carrier, and having a notch formed therein permitting downward movement of either the recorder or reproducer into engagement with a record on said carrier, and manual means to actuate said lever.

3. In a recording and reproducing device the combination of a rotatable disc record carrier, a carriage arranged for movement in a plane spaced above the plane of the record carrier, recording and reproducing devices operatively supported on said carriage and adapted for joint movement relative thereto in a plane parallel to and spaced from the plane of the record carrier and independent movement in a plane substantially normal to said last mentioned plane to engage a record on said carrier, and a single manual means effective to move said devices to cause one or the other to engage a record on said carrier.

4. In a recording and reproducing device, the combination of a record carrier, a carriage arranged for movement in a plane parallel with, and spaced above, the plane of the record carrier, recording and reproducing heads operatively mounted on said carriage and tending to move downwardly into operative position in engagement with a record on said carrier, actuatable means to selectively retain one or the other, or both of said heads in inoperative position above said record, and a single manipulative means to actuate said last mentioned means to cause one or the other of said heads to move to operative position.

ARNO RYSICK.
